[57] CLAIM

The ornamental design of a medication injector, as shown and described.

DESCRIPTION

FIG. 1 is a top plan view of the medication injector with the plunger extended showing our new design;

FIG. 2 is a side view thereof;

FIG. 3 is a bottom view thereof;

FIG. 4 is a side view thereof as seen from the side opposite of FIG. 2;

FIG. 5 is a front end view thereof;

FIG. 6 is a rear end view thereof;

FIG. 7 is a top plan view of the medication injector with the cap removed;

FIG. 8 is a side view thereof;

FIG. 9 is a bottom view thereof;

FIG. 10 is a side view thereof as seen from the side opposite FIG. 8;

FIG. 11 is a front end view thereof;

FIG. 12 is a rear end view thereof; and,

FIG. 13 is a top plan view of the medication injector showing the plunger in a depressed position.
